UNITED STATES PATENT OFFICE.

HERBERT PEARCE AND THOMAS ROBERT GILLETT PARKER, OF BROADHEATH, ENGLAND, ASSIGNORS TO LINOTYPE AND MACHINERY LIMITED, OF LONDON, ENGLAND.

ROTARY OFFSET-PRINTING PRESS.

1,215,404.

Specification of Letters Patent. Patented Feb. 13, 1917.

Application filed November 12, 1913. Serial No. 800,443.

To all whom it may concern:

Be it known that we, HERBERT PEARCE and THOMAS ROBERT GILLETT PARKER, subjects of the King of the United Kingdom of 5 Great Britain and Ireland, and residing at Linotype and Machinery Works, Broadheath, in the county of Chester, England, have invented new and useful Improvements in Rotary Offset-Printing Presses, of which 10 the following is a specification.

This invention relates to improvements in that class of rotary offset printing press which is adapted to print alternatively two color or perfector work, and it has, among 15 its principal objects, to provide a press having two plate cylinders, two transfer cylinders each of the latter in operative contact with one of the plate cylinders, and a single impression cylinder coöperating with both 20 of the transfer cylinders, the said five cylinders being arranged with their axes in planes forming approximately an equilateral triangle, those of the two plate cylinders being in a plane below, and that of the 25 impression cylinder being in a plane above, the axes of the transfer cylinders.

Hitherto, in printing presses of the above-named class, considerable trouble has been experienced owing to the difficulty with 30 which access could be had to the various cylinders thereof for inspection, cleaning and other purposes, and a special advantage secured by the present invention is the elimination or minimizing of the said difficulties, 35 this result being attained by the aforesaid relative arrangement of the cylinders and their location at such height in the press that they are all well within the view of the operator when he is standing on the floor 40 level.

The invention is also advantageously applicable to rotary perfecting presses.

In the accompanying drawings which are to be taken as part of this specification and 45 read therewith:

Figure 1 is the left hand part and Fig. 1^a the right hand part of an elevation, as viewed from the gear side, of a press according to the present invention;

50 Fig. 2 is a plan of part of the mechanism of the press shown in Fig. 1, with a certain

member thereof,—to wit—the yoke 38 represented diagrammatically;

Fig. 3 is an elevation, as seen from the underside of Fig. 2, with some of the parts 55 omitted;

Fig. 4 is an elevation, as seen from the left-hand side of Fig. 2;

Figs. 5 and 6 are diagrammatic views 60 illustrative of the operation of the press when producing multi-color printing, and

Figs. 7, 8 and 9 are diagrammatic views 65 illustrative of the operation of the same press when producing perfected printing.

The several figures are drawn to different 65 scales and throughout these figures like reference numerals are used to indicate like or corresponding parts.

In the form of the press represented 70 there are provided two plate cylinders 1, 2 both of the same diameter, supported in bearings 3, 4 respectively, in the two side frames 5 of the press; of these frames only that at the gear side of the press is shown in the drawings. In peripheral contact with 75 each of the plate cylinders 1, 2, there is provided a rubber—or equivalently—clothed transfer cylinder 6, 7, respectively, the diameter of each of which is half that of the respective plate cylinder 1, 2. 80

The two transfer cylinders 6, 7 are in operative contact with a single impression cylinder 8, the diameter of which is also half that of each of the plate cylinders 1, 2, or, in other words, of the same diameter as 85 each of the transfer cylinders 6, 7.

The transfer cylinders 6, 7, are supported in bearings 9, 10, respectively, in the side frames 5, and the shaft 11 of the impression cylinder 8, is journaled in eccentric bushes 90 or bearings 12 which are capable of being turned angularly in bearing boxes 13 which are themselves capable of being raised and lowered in vertical guides in the side frames 5. 95

The axes of the plate cylinders 1, 2, and impression cylinder 8 are situated in planes forming approximately an equilateral triangle, that of the impression cylinder being uppermost and at the apex of such triangle, 100 in a vertical plane midway between the axes of the plate cylinders, which last named

axes are in the same horizontal plane, while the axes of the transfer cylinders 6, 7, are situated slightly above or outside the two reversely inclined planes in which are situated 5 the axes of the impression cylinder 8 and the respective plate cylinder 1 or 2.

Under each of the bearing boxes 13 there is provided a helical spring 14, (one of which is shown in dotted lines in Fig. 1^a) 10 exerting a constant lifting effort on the impression cylinder 8, and attached by a pivot 15 to each such bearing box, is the upper end of a short eccentric rod or link 16 whose lower end encircles an eccentric 17 fast to a 15 shaft 18 capable of being rocked about a stationary axis, and having fast thereon a lever arm 19. To the swinging end of the lever arm 19 is pivoted the upper end of a preferably adjustable rod or link 20 whose 20 lower end is similarly connected to a crank arm 21 fast to a rocking shaft 22.

The rocking shaft 22, receives its rocking motion from a toothed sector lever 23 oscillated about a stationary pivot 24 by a 25 grooved cam 25 preferably on the end of the plate cylinder 1, this sector lever 23 gearing with a toothed segment 26 mounted loosely upon the rocking shaft 22. The toothed segment 26 is provided with two oppositely directed abutments 27, 28 with the former of which are capable of being engaged two separate pawls 29 and 30^a, and with the latter of which is capable of being engaged a pawl 30. The pawls 30 and 30^a 30 are integral with each other and constitute a double-ended pawl, and this double-ended pawl and the pawl 29 are respectively pivoted on lever arms 32 and 31 mounted on, but normally free from the rocking shaft 22. 40 In Fig. 4, the pawl 30^a is immediately in front of, and practically obscures from view, the pawl 29.

The bosses of the last-named lever arms 31, 32, are provided with clutch members or 45 faces 33, 34 respectively, with which can be engaged corresponding clutch members or faces 35, 36 axially slidable on the rocking shaft 22 but splined thereto by feathers 37, these two clutch members 35, being rigidly 50 secured together as by a yoke or bridge 38, so that when say, as is illustrated in Figs. 2 and 3, the clutch member 35 is moved into engagement with the corresponding clutch member 33, the clutch member 36 is correspondingly moved out of engagement with the clutch member 34 and when, reversely, the clutch member 36 is engaged with 34, then 35 is disengaged from 33; there is an 55 intermediate position in which both of the clutch members 35 and 36 are simultaneously disengaged from the respective members 33, 34.

On the rocking shaft 22 there is also 60 loosely pivoted a cam 39, see particularly Fig. 4, which, through an arm 40 integral

therewith, and well-known link and lever devices 41, is connected to a pedal 42 capable of being depressed and released by the operator, this cam 39, being so arranged that when the pedal 42 is depressed, it (the 70 cam) will be moved angularly about the rocking shaft 22, into the path of an anti-friction roller 43 pivoted on the before-mentioned pawl 29, so that when the roller 43 reaches the said cam, the pawl 29 will, 75 against the action of its controlling spring 44, Fig. 4, be moved out of engagement with the abutment 27 on the toothed segment 26.

The pedal 42 is connected, in well-known manner, with a grooved cam 45 which engages with an anti-friction roller 46 on the before described double-ended pawl 30, 30^a, this cam serving to move the end 30 of the said pawl out of and into engagement with the abutment 28 on the toothed segment 26, the pawl being so engaged when the pedal 42 is depressed, and disengaged when under the influence of a spring 47, the pedal is elevated.

A tooth 48 fast to the before-mentioned 80 lever arm 31 extends laterally from that arm into the path of the abutment 28 and, when engaged by the said abutment, serves to turn that arm clockwise and thereby effect a lifting of the impression cylinder 8 95 off impression.

Each of the before described eccentric bushes 12 has fast thereto or integral therewith, a lever arm 49 to which is pivoted the upper end of a preferably adjustable eccentric rod 50 whose lower end embraces an eccentric 51 fast on a second rocking shaft 52. This rocking shaft 52 has loose upon it, a spur pinion 53 which meshes with the lower end of a toothed sector lever 54 pivoted upon a stationary stud 55 and on whose upper end is pivoted an anti-friction roller engaging with a grooved cam 56 on the end of the plate cylinder 2. The pinion 53 is provided on one side with a clutch face 57, Fig. 2, with which is capable of engaging a movable clutch member 58, splined to the rocking shaft 52 by feathers 59, and embraced by a collar 60 fitting loosely in an annular groove in the said member. This collar 60, is connected by a link 61 (shown in dotted lines in Figs. 2 and 4) to one arm of a two-armed lever 62; the other arm of this lever is swiveled to a collar 63, loosely 100 engaged an annular groove in the before-described clutch member 58 and, through this member, and the yoke 38, it is also connected to the clutch member 35. 105

The lever 62 is fast to a short vertical shaft 64 which is free to be turned about its vertical axis in a stationary bracket bearing 65 fast to the adjacent side frame 5, the said shaft, for this purpose, having secured thereto a lever handle 66, Figs. 2, 3 and 4, which extends through the adjacent side 110 115 120 125 130

frame 5 to a position in which it can be conveniently manipulated by the operator.

When the before-described press is to produce two impressions on the same side of a sheet, as in multi-color work, a sheet is fed from the feed board 67, to the impression cylinder 8 at every alternate rotation of the latter, and each such sheet receives two successive superimposed impressions one from each of the two transfer cylinders 7, 6 (which have previously received the impressions from the respective plate cylinders 2, 1) the sheet subsequently being delivered by a chain or other delivery mechanism 68, on to the delivery board 69, either printed side up or down.

The operations of the before-described press will now be described by reference to the diagrams shown in Figs. 5 to 9 in which the various arrows indicate the directions of rotation of the different cylinders.

In these diagrams 1^a and 2^a indicate the plate or printing surfaces on the plate cylinders 1, 2 respectively; 6^a and 7^a the rubber or equivalent transfer blankets of the transfer cylinders 6, 7 respectively; 6^b and 7^b the reel rods by which the said blankets are stretched around the respective supporting surfaces of the cylinders 6, 7; 8^a the grippers which secure the sheets to the impression surface 8^b of the impression cylinder 8; 67 the feed board, and 68 a chain or other delivery which is capable of delivering the sheets printed side up or down on to the delivery board 69.

When the press is to produce two impressions on the same side of the sheets, as in multi-color work, the before-described clutch mechanism is in the condition of adjustment in which it is shown in Figs. 2 and 3, so that of the two rocking shafts 22, 52, only 22 will, for the time-being, be rocked, and the lever arm 32 and double-ended pawl 30, 30^a will remain inoperative. The pedal 42, being then in its raised position, the cam 39 will be in the position in which it is shown in Fig. 4, so that the pawl 29 will remain in the path of the abutment 27 and consequently the shaft 22 will be continuously rocked anti-clockwise by that pawl to lower the impression cylinder, and clockwise by the tooth 48 to raise the said cylinder. If now, the pedal 42 is depressed, the cam 39 is brought into the path of the roller 43 and effects the movement of the pawl 29 out of the path of the abutment 27, and simultaneously therewith the grooved cam 45 is raised so as to move the pawls 30 and 30^a respectively into and out of engagement with the abutments 28, 27, with the result that, at the next succeeding clockwise turn of the shaft 22, effected through the engagement of the abutment 28 with the tooth 48 and the mutual engagement of the clutch members 33, 35,

the lever arm 21 will also be moved clockwise and the impression cylinder 8 thereby raised, and since there is then neither of the pawls 29 or 30^a in the path of the abutment 27, the impression cylinder will remain tripped until the pedal is next released. With the press adjusted as aforesaid in the manner represented in Figs. 2 and 3, that is, so far as the clutch mechanism is concerned, the sheets are fed from the feed board 67 to the grippers 8^a, one such sheet at each alternate rotation of the impression cylinder 8. Through the rocking shaft 22, Figs. 1 to 4, the impression cylinder is, at that juncture raised off impression as represented in Fig. 5, and is maintained in that condition until the grippers 8^a arrive at the position in which they are shown in Fig. 6, so that throughout that period no impression is transmitted by the transfer cylinders 6, 7. When the grippers 8^a have arrived at or about the position in which they are shown in Fig. 6, the shaft 22 has rocked anti-clockwise and brought the cylinder 8 down on impression or in printing position as shown in Figs. 1 and 1^a, so that the sheet will receive first an impression from the transfer cylinder 7 and then another impression superimposed or not on the first one, from the transfer cylinder 6. The last-named printing relationship of the impression cylinder 8 relatively to the transfer cylinders 6, 7 is maintained until the following or tail end of the impression surface 8^b has passed out of printing contact with the transfer surface 6^a, at which juncture the shaft 22 is rocked clockwise and the impression cylinder is thereby again raised off impression.

When the grippers 8^a are presented above the axis of the impression cylinder 8, they are opened to release the sheet which is then seized, in well-known manner, by the delivery mechanism 68 which afterward drops it on to the delivery board 69. At the next succeeding rotation of the impression cylinder 8, a sheet is engaged by the grippers 8^a and the just-described sequence of operations is repeated.

When the press is to be used for perfecting, the impression cylinder 8 is clothed with an offset blanket, represented in Figs. 7, 8 and 9 by the curved dotted line 70, and the lever handle 66 is moved leftward (i. e., upward in Fig. 2) so as to disengage the clutch face 35 from 33 and engage the clutch faces 36 and 58 with 34 and 57 respectively and thereby bring both of the rocking shafts 22 and 52 into operation.

When the press is being thus used for perfecting, the impression cylinder 8, requires to be raised off impression only in the event of failure in the feeding of a sheet to it and this is effected by depressing the pedal 42 as previously described in connection with the

multi-color printing, and although the impression cylinder 8 will still continue to be rocked through the eccentric 51, it will not come into contact with the transfer cylinders 6, 7 until after the pedal is next released. With the press thus operating, the offset blanket 70, at every alternate rotation of the impression cylinder 8, receives a re-transferred impression from the blanket 7^a during 10 a period at which, through the rocking shaft 52, the impression cylinder 8 is, as shown in Fig. 7 out of printing contact with the transfer cylinder 6. At the next ensuing rotation of the impression cylinder 8, a sheet is fed to the grippers 8^a and through 15 the rocking shaft 52, the impression cylinder 8 is moved out of, and into contact with the transfer cylinders 7 and 6 respectively, so that when the sheet passes between the 20 cylinders 6 and 8 it receives impressions from both of them on its respectively opposite sides. After the tail of the sheet has passed from between the cylinders 6 and 8, the rocking shaft 22 effects the raising of the 25 impression cylinder 8 as shown in Fig. 9, and, prior to this raising of the cylinder, the sheet has been engaged by the grippers of the delivery mechanism 68. Just before, the grippers 8^a, during this delivering rotation reach the line joining the axes of the 30 cylinders 7, 8, the cylinder 8 is lowered into contact with the cylinder 7, as shown in Fig. 7, so as to receive a re-transferred impression from the last-named cylinder and 35 thereby commence a sequence of operations similar to that previously described.

71 and 72 represent respectively the damping and inking mechanisms which may be of any desired construction, and between 40 which there is provided sufficient space to admit of free access being had to the respective printing plates for cleaning or other purposes.

Copies of this patent may be obtained for five cents each, by addressing the "Commissioner of Patents, Washington, D. C."

Having described our invention, we declare that what we claim and desire to secure 45 by Letters Patent is:—

1. A rotary offset printing press having in combination two plate cylinders, two transfer cylinders each in operative contact with one of the plate cylinders, and a single 50 impression cylinder coöperating with both the transfer cylinders, the five said cylinders being arranged with their axes in planes forming substantially an equilateral triangle, those of the two plate cylinders being 55 in a plane below and that of the impression cylinder being in a plane above the axes of the transfer cylinders, and means for tripping and untripping the impression cylinder with reference to either both transfer 60 cylinders simultaneously or either cylinder independently of the other.

2. A rotary offset printing press having in combination two plate cylinders, two transfer cylinders each of the latter in operative contact with one of the plate cylinders, and a single impression cylinder coöperating with both of the transfer cylinders, the five 65 plate, transfer and impression cylinders being arranged with their axes in planes forming substantially an equilateral triangle, those of the two plate cylinders being in a plane below, and that of the impression cylinder being in a plane above, the axes of the transfer cylinders, and means operative 70 to move the impression cylinder off impression with the two transfer cylinders either 75 in alternation or simultaneously.

In witness whereof we have hereunto set out hands in the presence of two witnesses. 80

HERBERT PEARCE.
